US0D1085708S

(12) **United States Design Patent** (10) Patent No.: **US D1,085,708 S**
(45) Date of Patent: ** Jul. 29, 2025

(54) **BAG**

(71) Applicant: **DELVAUX CREATEUR SA**, Brussels (BE)

(72) Inventor: **Marc Valeanu**, Brussels (BE)

(**) Term: **15 Years**

(21) Appl. No.: **35/520,736**

(22) Filed: **Mar. 11, 2024**

(80) **Hague Agreement Data**

Int. Filing Date: **Mar. 11, 2024**

Int. Reg. No.: **DM/236656**

Int. Reg. Date: **Mar. 11, 2024**

Int. Reg. Pub. Date: **May 3, 2024**

(30) **Foreign Application Priority Data**

Sep. 25, 2023 (EM) 015034949-0001

(51) **LOC (15) Cl.** **03-01**

(52) **U.S. Cl.**

USPC **D3/246**

(58) **Field of Classification Search**

USPC D3/232–233, 239, 242–243, 245–246

CPC .. A45C 3/06; A45C 13/02; A45C 3/00; A45C

5/06; A45C 3/08

See application file for complete search history.
